APPARATUS FOR THE CONTROL OF HIGH-WAY CROSSING SIGNALS

Samuel Miskelly, Downers Grove, Ill., assignor to
Western Railroad Supply Company, Chicago,
Ill., a corporation of Illinois

Application April 7, 1939, Serial No. 266,547

11 Claims. (Cl. 246—130)

The present invention relates to railroad warning signals in general and particularly to a signaling system designed to accommodate the modern railroad's high speed trains as well as its relatively slow trains. More specifically, the invention comprises a signal-operating system for railroad-highway crossings in which the crossing signals are operated a predetermined time period before the train arrives at the crossing regardless of the train speed.

The present application is in part a substitute for earlier filed application Serial No. 198,005, filed March 25, 1938.

It is an object of the present invention to provide a new and novel train actuated highway-railroad grade crossing signal control system. It is another object of the invention to provide a crossing signal operating system for railroads which causes the signals to be operated at a predetermined time interval before the train reaches the crossing. Still another object of the invention is to provide a crossing signal operating system for railroads which directly gauges the train speed and operates the signaling mechanism in accordance therewith. A further object of the invention is to provide a signal operating system for railroads in which the speed of the train thru a short track section determines the time of signal operation. An additional object of the invention is to provide a crossing warning system for railroads in which a simple and reliable mechanism making use of a minimum track circuit length causes the crossing signal to be operated at a predetermined time interval before the train reaches the crossing. These and other more specific objects will be apparent from reading the following specification and upon considering in connection therewith the attached drawings.

Referring now to the drawings in which a preferred embodiment of the invention is disclosed:

Figure 1 is a diagrammatic illustration of the system comprising the present invention in the track-clear condition;

Figure 2 is a diagrammatic illustration of the time delay mechanism's electrical circuit only, with the track clear and in the condition illustrated in Figure 1;

Figure 3 is a diagrammatic illustration of the electrical circuit only with a train in track section A—B and moving in the direction of the crossing;

Figure 4 is a diagrammatic illustration similar to Figure 2 with the train in section B—C, hav-

ing entered from A—B and before the signal is operated.

Today train speeds vary within a very wide range and signaling systems once adequate are now obsolete. The advent of the high speed train in particular has made necessary the reconsideration of signaling system for such trains using tracks provided with a signal system designed for earlier and slower trains will reach the crossing before a reasonable minimum warning period will have elapsed. If the signal-operating mechanism of the old type is re-positioned on the track so as to be operated when the train is farther from the crossing in order to give the required warning of the approach of the high speed trains, then the slower speed trains take an undue length of time to reach the crossing after signal operation and public dissatisfaction follows. In the signal-operating system constructed in accordance with the present invention regardless of train speed a predetermined and reasonable period always exists between signal operation and train arrival at the crossing.

Referring again to the drawings, and to Figure 1 in particular, a preferred embodiment of the invention is illustrated. A railroad track 1 is seen to approach and to cross a highway 2. On its approach side the track 1 is divided into sections A—B, B—C, and C—D, each rail of each section being insulated at its end from the adjacent track. Across the rails of each section is a battery or equivalent source of potential, indicated by the reference characters 3, 4 and 5 for sections A—B, B—C and C—D, respectively. Each section also has its normally energized relay, indicated in the same order by the characters 6, 7 and 8 thru which current flows, with the section clear, from the section battery. Adjacent the track 1 at its crossing with the highway 2 is a signal, indicated generally by the reference character 9, which is to be operated at a predetermined time interval before the train reaches the crossing and which may be of any well known type and include flashing, lights, bells and gate arms if desired.

To effect this desired operation of the crossing signal there is provided a time-delay mechanism, now specifically described, which is actuated by a train passing thru the sections and operating the relays which are parts of an electrical circuit. The time-delay mechanism comprises an electric motor M having a field F and a shaft 12. Motor M is of a variable speed type adapted to be controlled by variations in the voltage impressed thereon. For this purpose a variable resistance

R is connected in series therewith which includes a plurality of taps R1, R2, R3, R4, etc.

Driven by the motor shaft 12 thru gears 14, 15, 16 and 17, with an intermediate shaft 18 between gears 15 and 16, and pinion 19 carried by a second shaft which is actuated by final gear 17, is a toothed rack 25 which is vertically slidable in its mounting base 26. Rigid upper and lower arms 28 and 29 extend laterally from the rack, for a purpose to be explained, and with a suspended weight 27 complete the vertically movable unit which is adapted to be lifted by the motor and to descend under the actuation of gravity turning the gears and motor as it does so.

A friction brake 32 is provided to lock the vertically movable unit in its uppermost position by exerting a locking force on the side of gear 14 under the actuating force of a solenoid 33 when the latter is energized, a tension spring 34 serving to hold the brake inoperative when the solenoid is unenergized.

To vary the motor speed there is provided a traveling contact 36 which is mounted by an insulator 37 upon an internally screw-threaded carrier 38. Carrier 38 is itself mounted upon an externally threaded shaft 39 which is actuated by a gear 40 driven by previously mentioned gear 15. Shaft 39 extends along the resistance R and the path of contact 36 is such that it successively contacts the stationary contacts R1, R2, R3, etc. to vary the resistance in the motor circuit.

The electrical circuits which operate the time delay mechanism and which are operated thereby are now described, particular reference being had to Figures 1 and 2 in which a track-clear condition is present.

The signal 9 at the crossing is of the normally energized type and in series therewith are the contacts 41A and 41B of the relay 41 which is controlled by the time-delay system. With current passing thru the relay 41 the signal 9 remains inoperative but with the relay 41 de-energized the signal is immediately operated.

First, with reference to the track relays, relay 6 of section A-B has a single movable contact 6A which is normally open and out of contact with stationary contact 6B. Movable contacts 7A and 7C of relay 7 in section B-C are normally closed with stationary contacts 7B and 7D, respectively, with relay 7 energized. In section C-D in relay 8 the contacts 8A and 8B are closed with the relay energized. The flow of current is primarily controlled by these relays as will be apparent.

A battery B is connected in series with motor M with its variable resistance R and controlling the flow of current to the motor are the train-controlled contacts 6A, 6B, 7A, 7B; and the rack-controlled movable and stationary contacts 42 and 43, all in series with the battery. Contacts 6A and 6B are normally open with section A-B clear and current passing thru relay 6, the other contacts being normally closed. With a train in section A-B, however, the relay 6 is shorted and contacts 6A and 6B closed and during such period the motor M rotates and at an increasing speed as hereinafter explained. The rack operated movable contact 42 is positioned in the path of rack-carried arm 28 and is adapted to be contacted thereby at its insulated end and moved from the stationary contact 43 and to a second stationary contact 44 as the rack substantially reaches the upper limit of its movement.

Also connected across the battery B and in series with contacts 6A, 6B, 7A, 7B; and 42, 44

is the brake solenoid 33. As rack-actuated contact 42 only closes with stationary contact 44 after the rack has moved substantially its full vertical displacement, and as current from the battery B can only pass therethru while contacts 6A, 6B and 7A, 7B respectively, are together, a condition which can exist only while a train is within section A-B, it follows that the brake 32 controlled by solenoid 33 will only be operated upon the passage thru A-B of the slowest train. The solenoid will remain energized only until the train has entered section B-C at which time relay 7 is de-energized and contacts 7A and 7B open. Also of interest is the fact that the closing of contacts 42 and 44 by rack arm 28 follows closely upon the opening of contacts 42 and 43 by the same arm. As the latter contacts are in series with the battery B and motor M it is evident that the motor current will be cut off slightly before contacts 42 and 44 close. The momentum of the moving parts insures the continuance of the rack travel to accomplish the latter result, however.

In another circuit including the battery B are the contacts 7C and 7D of relay 7, 8A and 8B of relay 8, and the winding of relay 41, the contacts 41A and 41B of which control the flow of current thru the signal 9. In parallel with the contacts 7C and 7D of relay 7 are normally closed contacts 46 and 47, the latter being movable and being adapted to be contacted at its insulated end by the lower arm 29 of rack 25 to be moved from contact 46 as the rack reaches the end of its downward travel. The opening of contacts 7C and 7D upon a train entering section B-C will not, therefore, serve to cut off the current thru the relay 41 until the rack has returned to its initial and lower position.

With the system starting in its normal condition, as illustrated in Figures 1 and 2, its operation will now be described. Let it be assumed now that a train has entered section A-B and is traveling in the direction of the highway 2. Immediately the train enters section A-B relay 6 is shorted and contacts 6A and 6B close and the circuit including the motor M and battery B is completed, as illustrated in Figure 3. In Figure 3 the train has been in section A-B for a period of time and the motor M has lifted the rack a distance which is determined as hereinafter explained and which is dependent upon the time period. The time period the forward end of train is in section A-B will be referred to as TAB. Contacts 46 and 47 have been closed as a result of the movement of rack-carried arm 29.

A fast train will traverse section A-B in a relatively short time for it is one of the advantages of the present invention that section A-B can be short which characteristic eliminates undesirable factors resulting from train speed variation in long sections. As described the motor M begins to rotate the instant the train enters A-B and the upward movement of rack 25 begins simultaneously. The motor speed is not constant, however, for as TAB increases the resistance R is cut out in successive steps and the motor speed increases. Accordingly the rack travel is not directly proportional to TAB but instead grows relatively greater as TAB increases.

Regardless of the train speed it is desired that the signal begin its operation a predetermined period before the train reaches the highway. This warning period is a constant which may be called K and can be taken, for example,

to be 20 seconds. Referring to Figure 1 the dotted line X—X is a variable position on the track between B and D at which the train is positioned when the signal begins operation. Let T_{BX} be the time required to travel the distance B to X for any particular train. Obviously for a fast train X will be farther from D than for a slow train for both are to reach the crossing during the same elapsed period from position X. It is clear that if the signal can be put into operation for each particular train when it reaches its X position that the desired result will accrue. It has been calculated that for any given train

$$T_{BX} = T_{AB} \cdot \frac{BD}{AB} - K$$

Where the constant K is decided upon and the distances A—B and B—D known, it is clear that T_{BX} can be calculated by substituting in the formula the value of T_{AB} . Of course T_{AB} is the time required by the train to travel the distance A—B, etc. As the range of train speeds is known the calculation can be done by assuming values of T_{AB} . It is of course obvious that the proper units must be used, for example, K, T_{AB} and T_{BX} in seconds and BD and AB in feet.

The formula is derived in the following manner:

$$(1) \quad \frac{T_{AB}}{T_{BD}} = \frac{AB}{BD}$$

and

$$(2) \quad T_{BD} = T_{AB} \cdot \frac{BD}{AB}$$

also

$$(3) \quad T_{BX} = T_{BD} - K$$

from which

$$(4) \quad T_{BD} = T_{BX} + K$$

substituting in (2) the value of T_{BD} in (4) gives

$$(5) \quad T_{BX} + K = T_{AB} \cdot \frac{BD}{AB}$$

or

$$(6) \quad T_{BX} = T_{AB} \cdot \frac{BD}{AB} - K$$

In the present device the rack 25 is raised during the time interval T_{AB} by the motor M and falls by gravity during the time interval T_{BX} . As is evident from the above formula T_{AB} and T_{BX} do not vary according to a straight line relationship and accordingly the rate of lifting of the rack 25 must be varied. The calculated relationship and desired time T_{BX} is automatically arrived at by the present device for each T_{AB} , for the motor speed is so varied that over the time interval T_{AB} which it takes the engine of a particular train to travel from A to B the rack 25 is lifted to a particular height such that its return to its initial position under the actuation of gravity will consume T_{BX} . As stated supra signal operation begins when rack-carried arm 29 opens contacts 46 and 47.

This desired relationship between motor speed or travel and rack travel may be obtained by determining the particular height to which the rack must be raised in order that it will consume a particular time T_{BX} in falling. The values of the resistance taps R1, R2, R3, etc. will be selected so that the motor will lift the rack to that height in the corresponding T_{AB} time. By beginning at the minimum times T_{AB} and T_{BX} and increasing the values thereof the position of each resistance tap is determined. If a relatively large

number of taps is found to be necessary they can be eliminated and a constantly varying tapless resistance substituted, which is arranged to give the same result. As the rack in its return movement remains geared directly to the motor thru the gear train it has a constant load and will travel at a substantially constant speed. In brief, the motor raises the rack at a variable, progressive rate in order that the rack will lower by gravity under load during the T_{BX} .

Let it be assumed now that the front of the train has passed point B and has entered section B—C. Referring particularly to Figure 4 in which this condition exists it is seen that relay 7 is now de-energized and contacts 7A and 7B as well as 7C and 7D are open. The first-mentioned pair have opened the circuit of the motor and the rack, under gravitational force, has begun its return to its initial position. While contacts 7C and 7D are open current continues to flow from the battery B thru the signal controlling relay 41 for the rack-controlled contacts 46 and 47 remain closed.

Signal operation occurs after the train has entered section B—C and T_{BX} has passed which has enabled the rack to return to its initial position and its arm 29 to open contacts 46 and 47 which opened the circuit thru the controlling relay 41 whereupon contacts 41A and 41B opened 30 and the signal began operation.

Upon the train passing from section BC the relay 7 again picks up and closes its contacts and the control mechanism is in its initial condition except the relay 8 which is a safety relay in section C—D and which only has an opportunity to operate the signal when failure has occurred and the signal has not been operated before the train reaches C. The contacts 8A and 8B are in series with the control relay 41 and should current be passing thru that element when the train reaches C their opening insures signal operation though somewhat tardy. After the train passes D the relay 8 picks up and the control relay 41 is again energized the signal is returned to its inoperative position.

One other safety feature comprises the solenoid controlled brake 32. Should the train be extremely slow and should the period T_{AB} be so great that the rack is lifted to its upper limit the arm 28 thereon opens contacts 42 and 43 and closes 42 and 44. The opening of 42 and 43 would effect the opening of the motor circuit, as is evident from a consideration of Figure 2 and the closing of 42 and 44 energized the solenoid 33 which caused the brake 32 to be applied to the side of gear 14. So long as the train remains entirely in section A—B only the brake will remain on but upon reaching B the opening of contacts 7A and 7B of relay 7 causes the solenoid to be de-energized and the brake released.

I claim:

1. In a signalling system for a highway crossing on railroads, the combination with a signal at a highway crossing, of a relatively short track section spaced from the crossing, a relatively long track section between the short section and the highway, and a signal operating device comprising: a movable element adapted to be wound up at a variable speed and to run down at a constant speed, a variable speed electric motor to wind up said element at a predetermined increasing rate during the time a train moves across the short section, means to vary the speed of said motor at a progressive rate and controlled automatically thereby to cause said mov-

able element to be displaced a distance such that it can return at substantially uniform rate to its initial position a predetermined time interval prior to the train reaching the crossing, and means to operate said signal upon the return of said element to its initial position.

2. In a signalling system for a highway crossing on railroads, the combination with a railroad track and a signal, of signal operating means comprising an element normally biased to an initial position and movable within limits upon the application of a moving force thereto and automatically returned to its initial position upon the removal of that force at a substantially constant speed, an electric motor energized during the movement of a train toward said crossing and between two points on the track means to effect rotation of said motor at an increasing rate of speed in accordance with a predetermined time-speed curve, means connecting said motor to said element to apply a moving force thereto, means disconnecting said motor as said train emerges from between said two points, said element returning to its initial position upon the de-energization of said motor, and means to actuate said signal upon return of said element to its initial position characterized in that the speed of rotation of said motor varies so that said element is displaced to an extent such that it returns to its initial position a fixed time period before the train reaches the signal.

3. In a signalling system for a highway crossing on a railroad, a short track section, a long track section adjacent at one end to said short track section and insulated therefrom, a highway crossing at the opposite end of said long section, a signal at the intersection of said railroad and highway, and means to operate said signal at a predetermined time interval before a train reaches said crossing regardless of the train speed, said means comprising a movable element normally biased to one position, an electric motor connected to said element and including speed varying means to progressively increase the motor speed in a predetermined manner during the traversal of said short track section by a train, means to energize said motor during the time required for a train to travel the short section, said motor functioning to move said movable element during such time a distance dependent directly upon the travel of said motor, means to de-energize said motor upon the entrance of a train into the long section, said element returning to initial position during the time period the train is in the long track section at a substantially uniform rate, characterized in that said motor speed is varied in a manner such that said element is lifted to a height for each train speed that it is returned at substantially uniform rate to its initial position a predetermined time interval before the train reaches the crossing.

4. In a signalling system for a highway crossing on a railroad, a short track section, a long track section adjacent one end of said short track section and insulated therefrom, a highway crossing at the opposite end of said long section, a signal at the intersection of said railroad and highway, and means to operate said signal at a predetermined time interval before a train reaches said crossing regardless of the train speed, said means comprising a movable element normally biased to one position, an electric motor connected to said element and subject to speed variation with variation in the voltage impressed thereon, means controlled by said motor to in-

crease progressively the voltage across said motor during its operation, means to effect the energization of said motor during the time interval required for a train to travel the short track section, said motor functioning to move said movable element during said time interval a distance dependent directly upon the travel of said motor, means to de-energize said motor upon the entrance of the train into said long track section, and means to effect the return of said movable element to its initial position with said train in said long track section at substantially uniform rate, characterized in that the variation in voltage to said motor causes the speed of said motor to vary to control the distance traveled by said movable element in a predetermined manner.

5. In a signalling system for a highway crossing on a railroad, a short track section, a long track section adjacent one end of said track section and insulated therefrom, a highway crossing at the opposite end of said long section, a signal at the intersection of said railroad and highway, and means to operate said signal at a predetermined time interval before a train reaches said crossing regardless of the train speed, said means comprising a movable element, means to place the signal into operation comprising a movable contact operable by said movable element, means to raise said movable element against gravity during the passage of a train thru the short track section, said means comprising a train-operated relay and a motor controlled thereby and connected to said movable element, motor speed controlling means operated by said motor to increase its speed to effect increased speed of travel in said movable element with said train in said short track section, means to de-energize said motor upon the train entering said long track section, said movable element being adapted to return by gravity to its initial position to operate said movable contact with said train in said long track section, characterized in that the speed of said motor is so controlled as to displace said movable element at a height such that it can fall by gravity to operate said movable contact a predetermined time period before said train reaches the end of the long track section.

6. The construction set forth in claim 4 further characterized in that means are provided upon a train traversing said short track section at less than a predetermined speed to de-energize said motor and to lock said movable element in place upon said movable element reaching the end of its upward travel.

7. In a signalling system for a highway crossing on a railroad, the combination with a plurality of insulated track sections at one side of a highway and a signal at the highway, of a system for operating the signal at a predetermined time interval before the train arrives at the crossing regardless of the train speed, said system including a vertically slideable element, an electric motor connected thereto and including a variable resistance, means to energize said motor during the movement of a train across a first track section, means to de-energize said motor upon the entrance of the train into a second track section, means operated by said motor to vary the resistance with the time of energization to control the motor speed, and means to operate said signal upon the return of said element to a predetermined position, characterized in that the resistance of said motor is varied in a predeter-

mined manner so as to cause said element to be lifted vertically a distance such that its return to said predetermined position at a uniform rate occurs at a predetermined time interval before the train reaches the signal for various periods of time required for a train to travel the first section.

8. In combination, a stretch of railroad track intersected by a highway, a highway crossing signal located adjacent the intersection, a member normally occupying one position, means for moving said member away from said one position at a progressively increasing speed during the time interval required for a train approaching said highway to traverse a fixed distance and including a variable speed motor directly connected thereto, means effective when the train has traversed said fixed distance for restoring said member to said one position at a uniform rate, and means responsive to the position of said member for controlling said signal.

9. In combination, a stretch of railway track intersected by a highway, a highway crossing signal located adjacent the intersection, a vertically slideable toothed rack normally occupying one position, means for raising said rack at a progressively increasing rate during the time interval required for a train approaching the highway to traverse a fixed distance and including a variable speed motor geared to said rack, means effective when said train has traversed said fixed distance to de-energize said motor to permit said rack to fall under gravity with said motor connected thereto, and means responsive to the position of said rack for controlling said signal.

10. In combination, a stretch of railroad track intersected by a highway, a highway crossing signal located adjacent the intersection, a member normally occupying one position, means for moving said member away from said one position during the time interval required for a train approaching said highway to traverse a fixed distance, means effective when the train has traversed said fixed distance for restoring said member to said one position, and means responsive to the position of said member for controlling said signal, characterized in that said member moves at a progressively increasing speed in one direction under the actuation of a variable speed rotor of an electric motor which automatically controls means for varying its own speed at a progressive rate and in that said member moves in the opposite direction at an uniform rate.

11. In combination, a stretch of railroad track intersected by a highway, a highway crossing signal located adjacent the intersection, a member normally occupying one position, means for moving said member away from said one position at a progressively increasing speed during the time interval required for a train approaching said highway to traverse a fixed distance and including a variable speed motor directly connected thereto, means effective upon said train traveling said fixed distance to de-energize said motor, gravity-actuated means to return said member to said one position against the braking effect of said motor, and means responsive to the position of said member for controlling said signal.
